GRAB FOR LIFTING MATERIALS

Sydney Herbert Priestman, Hull, England, assignor to Messrs. Priestman Brothers Limited, Hull, York, England, a company of Great Britain

Application June 10, 1946, Serial No. 675,559½
In Great Britain June 23, 1945

3 Claims. (Cl. 294—112)

1

This invention relates to grabs of a type in which the jaws are adapted to be spread widely apart by the use of lazy-tongs linkage, the opening and closing of the grab being controlled by separate opening and closing ropes passing round sheaves connected to the lazy-tongs linkage.

In the operation of grabs of the type in question it has been found that it is possible under some conditions for the jaws to be pushed inwards from the fully expanded position when the grab is opened and is being lowered upon material to be lifted. This can occur for example when the grab is working upon a sloping face of the material to be lifted in which case the grab as a whole may tend to fall downwards on top of the jaw on the lower side, thus causing it to fold inwards, and nothing which the operator can do by manipulating the ropes can prevent this. The upper jaw may then also fold in under gravity as the grab tilts.

It is the object of the present invention to overcome this defect which only arises under certain conditions and may not be noticed when such a grab is generally being lowered upon more or less even layers of spoil to be lifted.

According to this invention the grab jaws or the brackets carrying them are extended beyond their pivots and are provided with eyes or shackles to which short lengths of chain or rope, herein-after referred to as chains, are connected. The other end of each such chain is secured to a lug or eyelet attached in a suitable position preferably to the lower link of the outer bay of the lazy-tongs on its own side of the lazy-tongs linkage. The length of each chain is such that, with the lazy-tongs linkage extended, the chain is stretched between its two end attachments so as to hold the jaw to which it is connected fully open. The jaws cannot therefore be folded inwardly when the grab is fully extended under the pull of the opening rope, but must remain in the digging position when lowered upon the spoil, even if the surface is sloping or irregular. The grab therefore commences to dig with the jaws extended but, as the closing rope is hauled in, the jaws are first turned inwardly toward the cutting position while the chains remain tight, after which the jaws are brought together by collapsing the lazy-tongs linkage and the chains become slack. The shovelling action of the grab is not therefore interfered with nor is its efficiency in any way reduced by the addition of the chains referred to above. Chains are preferably used as they hang down freely when slackened

2

and are not liable to kink, but in place of chains, ropes or any other suitable connections such as linked rods can of course be used if they are so disposed as not to foul other parts of the grab structure as they fold.

The invention is illustrated in the accompanying drawings in which:

Figure 1 shows a side elevation,

Figure 2 shows an end view,

Figure 3 shows a side elevation in the extended position, and

Figure 4 shows a side elevation of a grab in accordance with the invention, with the lazy linkage closed and the jaws open.

(Each of these first four figures shows a grab of the type having curved tines for digging fibrous material, such as manure).

Figure 5 shows a side elevation in the closed position, and

Figure 6 a partial side view in the extended position of a grab according to the invention with buckets suitable for handling materials such as ores.

Referring first to Figures 1 and 2, the lazy-tongs linkage has three bays, the upper links *a* of the outer bays having long downwardly-extending limbs providing pivots at their ends for brackets *c* carrying the grab jaws *d*, which in this example are curved tines supported at spaced intervals apart in crossbars *e*. These crossbars extend through and beyond the brackets *c* at each side of the grab.

The brackets *c* are pivoted between the jaws to links *f* at *g*. The links *f* extend upwardly and have slots at *h* in their upper ends working over pins *i* projecting from the lower links *j* of the outer bays of the lazy-tongs in this case. The slotted links *f* carry pairs of sheaves *k* around which passes the closing rope *m*. One end of this rope is suitably anchored to a point on the linkage, for example by a tab *l* to the pivot *n* between links *j* and *a* as shown. From the tab *l* the rope passes round sheave *k* on one slotted link *f* across to the corresponding sheave *k* on the opposite slotted link *f*, thence up to a sheave *o* turning on pivot pin *p* of the outer joint of the lazy-tongs on that side of the grab head, back from sheave *o* to a second sheave *k* on the same side of the grab head, across the grab head to a second sheave *k* on the other side, and then upwardly round a sheave *q* carried by brackets *r* upon the top middle bay of the lazy-tongs.

From sheave *q* the rope *m* extends up to the jib as usual. The rope *m* is called the closing rope. A second rope *s* called the holding rope or

opening rope, has one end connected at u to an extension of bracket r from which the rope is carried round a sheave t on the bottom pivot of the middle bay of the lazy-tongs linkage, and up round a second sheave q^1 beside sheave q in the bracket r , whence the rope s also passes up to the jib.

So long as the whole weight is taken by rope s , while rope m is slackened, the upper and lower links of the middle bay of the lazy-tongs are drawn together so causing the lazy-tongs linkage to expand as indicated in Figure 3. On the other hand, if the rope s is slackened while the rope m is pulled up, to take the whole weight, the lazy-tongs linkage is contracted and the jaws d are brought together as shown in Figure 1. In the closed position the pins i are at the bottom of slots h in links f , these links f being drawn together and pulled up by the tension of rope m . The tines or jaws d are then closed because the brackets c have their pivots g drawn up relatively to the pivots b .

According to this invention chains or ropes w (hereinafter referred to as chains) are provided connected at one end as at z to link j and at the other end as by shackles y to extensions x of one of the brackets c beyond the pivots b at each side of the grab. When the jaws are closed by pulling on the closing rope m the chains w hang loosely as indicated in Figure 1. When the jaws are opened fully by slackening rope m and pulling rope s , the parts of the linkage and the jaws take up the position shown in Figure 1, in which the links are lettered a^2 , f^2 and i^2 , the bottom brackets c^2 and the jaws d^2 . In this position the chains w are tight as indicated at w^2 , so holding the jaws positively in their fully extended position.

It is in this position that the grab is lowered upon the heap of spoil to be lifted, and even if the spoil is on a slope or is otherwise uneven, there is no risk that the jaws will fold inwardly under the weight of the grab. For engaging the spoil the closing rope m is now pulled while rope s is slackened, and the first effect is to draw inwardly the sheaves k and links f , causing the slotted ends h to slide up over pins i , the jaws being turned inwardly to the cutting position ready for being brought together to engage and lift the spoil. The chains w are still tight, but the movements of the links to the extent required are not impeded. In fact in changing from position d^2 of the jaws or tines, the chains w by their tension prevent the lazy-tongs linkage from collapsing upon the jaws and so control the change of position of the linkage. Further pulling on the closing rope m now draws the jaws together to take up a load of spoil, while the chains w become slack, and the parts finally reach position of Figure 1.

For discharging the load of spoil, the closing rope m is paid out to some extent with respect to the rope s , allowing the sheaves k to drop with links f and brackets c under the load on the jaws until the links and jaws occupy the positions indicated by references f^1 , c^1 and d^1 in Figure 3. Further paying out of rope m while the weight is taken by holding rope s causes the linkage to expand and the jaws to open fully as already described and indicated by the reference letters a^2 , f^2 , c^2 and d^2 in Figure 3, while the chains w tighten as at w^2 .

In Figures 5 and 6 a grab with buckets suitable for ore-handling and similar purposes is shown in the closed and open positions respectively, and

the corresponding parts are given reference letters in capitals (A to Z). The jaws when opened to discharge the spoil are lettered D^1 ; when opened to their maximum spread they are lettered D^2 , and when drawn in to the level cutting spread they are lettered D^3 . Other parts are lettered A^2 and A^3 , B^2 and B^3 , and so forth to denote their corresponding positions. There are a few casual differences in construction which may be noted. There are no brackets such as c , Figure 1, as the jaws D are directly pivoted at B to the links A , and at G to links F . In place of pins i engaging in slots h in links f , Figures 5 and 6 show the links F made with long straight upper ends sliding in guides H which are pivoted at I to links J . The closing rope M and opening rope S are guided and operated in the same way as ropes m and s of Figures 1 and 2. The chains W are also similarly connected and serve the same purpose. It is thought that Figures 5 and 6 can be understood from the description of Figures 1 and 2, and the corresponding lettering without further explanation. Some of the parts of the linkage are only indicated by centre lines or centre points in the cutting position, as at A^3 and J^3 .

I claim:

1. A grab of the lazy-tongs type comprising a lazy-tongs linkage with downwardly prolonged end link members, a pair of jaws and means pivotally connecting them to said downward prolongations of the end link members, additional links connected to each of such jaws and means providing a sliding connection for such additional links with elements of said lazy-tongs linkage, an opening rope and a closing rope, sheaves on such lazy-tongs linkage about which said opening rope passes, sheaves on said linkage and on said additional links about which said closing rope passes, extensions associated with said jaws beyond their pivotal connections to the downward prolongations of the end members of the lazy-tongs linkage, and flexible connections between said extensions and the lazy-tongs linkage, said flexible connections being of such length as to hold said jaws fully opened in the expanded position of said lazy-tongs linkage.

2. A grab of the lazy-tongs type comprising a lazy-tongs linkage with downwardly prolonged end link members, a pair of jaws and means pivotally connecting them to said downward prolongations of the end link members, additional links connected to each of such jaws and means providing a sliding connection for such additional links with elements of said lazy-tongs linkage, an opening rope and a closing rope, sheaves on such lazy-tongs linkage about which said opening rope passes, sheaves on said linkage and on said additional links about which said closing rope passes, extensions associated with said jaws beyond their pivotal connections to the downward prolongations of the end members of the lazy-tongs linkage, lengths of chain connecting each of said extensions to elements of the lazy-tongs linkage, such lengths of chain being so dimensioned that they become tight and hold said jaws fully opened in the expanded position of said lazy-tongs linkage while it is under the pull of the opening rope.

3. A grab of the lazy-tongs type comprising a lazy-tongs linkage with downwardly prolonged end link members, a pair of jaws and means pivotally connecting them to said downward prolongations of the end link members, additional

links connected to each of such jaws and means providing a sliding connection for such additional links with elements of said lazy-tongs linkage, an opening rope and a closing rope, sheaves on such lazy-tongs linkage about which said opening rope passes, sheaves on said linkage and on said additional links about which said closing rope passes, extensions associated with said jaws beyond their pivotal connections to the downward prolongations of the end members of the lazy-tongs linkage, lengths of chain connecting each of said extensions to elements of the lazy-tongs linkage, such lengths of chain being so dimensioned that they become tight and hold said jaws fully opened in the expanded position of said lazy-tongs linkage while it is under the pull of

5 the opening rope, and that said lengths of chain remain tight when the closing rope is operated to the extent required to turn said jaws inwardly to the cutting position, but become slack when the lazy-tongs linkage is collapsed under the pull of said closing rope.

SYDNEY HERBERT PRIESTMAN.
